GUIDE MECHANISM FOR A MEDICAL CATHETER

Clair E. Cox, Winston-Salem, N.C., and Frank Hinman, Jr., San Francisco, and Andrew Harautuneian, Gardena, Calif., assignors to Pharmaseal Division of American Hospital Supply Corporation, Glendale, Calif., a corporation of Illinois

Filed Nov. 21, 1968, Ser. No. 14,574

Term of patent 14 years

Int. Cl. D24—03

U.S. Cl. D83—12

FIG. 1.

FIG. 2.

FIG. 3.

FIG. 4.

FIGURE 1 is a right side elevational view of the guide mechanism for a medical catheter, a left side elevational view being a mirror image of the right side elevational view;

FIGURE 2 is a top plan view thereof, a bottom plan view being a mirror image of the top plan view;

FIGURE 3 is a left end elevational view thereof; and

FIGURE 4 is a right end elevational view thereof.

We claim:

The ornamental design for a guide mechanism for a medical catheter, as shown and described.
